(57) **CLAIM**

The ornamental design for a false battery electronic article surveillance device, as shown and described.

DESCRIPTION

FIG. 1 is a perspective view of the false battery electronic article surveillance device showing my new design;

FIG. 2 is a top plan view thereof;

FIG. 3 is a bottom plan view thereof;

FIG. 4 is a front view thereof with the rear view being identical;

FIG. 5 is a left side view thereof with the right side view being identical; and,

FIG. 6 is a perspective view thereof shown in a position of use within a portable CD player.

The portions shown in broken lines are included for illustrative purposes only and form no part of the claimed designs.

1 Claim, 3 Drawing Sheets
